William B. Ruger, Southport, Conn.

Filed Aug. 20, 1959, Ser. No. 57,237

Term of patent 14 years

(Cl. D30—1)

FIG. 1 is a side elevation of a revolver showing my new design.

FIG. 2 is a top plan view of FIG. 1 with portions of the broken line structure omitted for convenience of illustration.

FIG. 3 is a front end elevational view with a portion of the broken line structure omitted for convenience of illustration.

FIG. 4 is a perspective view of the rear sight portion of the revolver.

The essential features of the design reside in the rear sight portion shown in full lines.

I claim:

The ornamental design for a revolver, as shown and described.
